(57) **CLAIM**

The ornamental design for a beverage holder, as shown and described.

DESCRIPTION

FIG. 1 is a front perspective view of a beverage holder according to the present invention.

FIG. 2 is a front elevation view of the beverage holder illustrated in FIG. 1.

FIG. 3 is a rear elevation view of the beverage holder illustrated in FIG. 1.

FIG. 4 is a left side elevation view of the beverage holder illustrated in FIG. 1.

FIG. 5 is a right side elevation view of the beverage holder illustrated in FIG. 1.

FIG. 6 is a top plan view of the beverage holder illustrated in FIG. 1; and,

FIG. 7 is a bottom plan view of the beverage holder illustrated in FIG. 1.

The broken lines in FIGS. 1 and 3-6 depict fasteners that are elements of the beverage holder that do not form a claimed feature of the present invention.
